DESIGN FOR A DRESS

Christos Capidaglis, Long Island City, N. Y.

Application November 27, 1940, Serial No. 96,881

Term of patent 7 years

To all whom it may concern:

Be it known that I, Christos Capidaglis, a citizen of the United States of America, residing in Long Island city, county of Queens and State of New York, have invented a new, original, and ornamental Design for a Dress, of which the following is a specification, reference being had to the accompanying drawing, forming part thereof, wherein,

Fig. 3 is a fragmentary front view of the dress showing one of the sleeves in a raised position.

I claim:

The ornamental design for a dress, substantially as shown.

CHRISTOS CAPIDAGLIS.
